UNITED STATES PATENT OFFICE

WILLIAM H. BAUCH, OF SHELBYVILLE, INDIANA, ASSIGNOR TO SONO EQUIPMENT CORPORATION, OF INDIANAPOLIS, INDIANA, A CORPORATION

RESILIENT SUPPORT FOR PHOTO-ELECTRIC CELL EXCITER

Application filed June 23, 1930, Serial No. 463,037. Renewed September 16, 1932.

This invention relates to a mounting for an exciter bulb to be used in connection with a photo-electric cell. The invention is particularly applicable to an apparatus used for 5 reproducing sound from so-called "sound films".

In ordinary use an exciter bulb is apt to be subjected to vibrations from exterior causes, such as the engagement of gears in the projecting apparatus. Such vibrations, when imparted to the filament of the exciter, are transmitted in the form of light variations to the photo-electric cell. When the vibration has a frequency falling within the sound wave 10 band a corresponding sound issues from the reproducing apparatus.

The principal object of this invention is to provide a mounting for such bulbs, by means of which these vibrations are not transmitted 15 to the filament.

The principal feature of the invention by which this object is obtained is the provision of a resilient support for said bulb. Such a support has in itself a natural period of 20 vibration, depending upon its resiliency. If this period of vibration does not coincide with that of mechanical vibrations from within or without the device, these vibrations are not transmitted to the filament. If the natural frequency of the support does coincide 25 with that of exterior vibrations, the said support vibrates in resonance therewith causing the same to vibrate and producing greatly increased sounds in the amplifier.

30 By means of another feature of the invention, means are provided by which the natural period of vibration of the support may be varied at will so that it may be adjusted not to coincide with that of the exterior vibrations.

Another feature of the invention resides in the provision of means by which this variation of natural frequency is accomplished without substantial variations in the position 35 of the exciter filament.

The features of the invention by which these and other objects are attained will be apparent from the accompanying drawing and the following description and claims:

40 Fig. 1 is a plan view of an exciter bulb

support embodying the invention. Fig. 2 is a side elevational view thereof. Fig. 3 is a front elevational view. Fig. 4 is a side elevational view of a portion of the apparatus as shown in Fig. 2.

The exciter mounting includes a base member 10 having two parallel openings 11 therein. The said openings are adapted to engage pins 12 carried upon any suitable support 13. A thumb screw 14 engages one of the pins 12 for maintaining the base member thereon in fixed position. At one end of the base member 10 there is fastened a downwardly-extending L-shaped member 15 of resilient material, to the lower end of which is fastened a horizontal bulb-supporting member 16. The member 15 acts as a resilient hinge support for said bulb-supporting member 16. A bulb socket 17 has a downwardly-extending threaded shank 18 passing through an elongated opening 19 in the bulb-supporting member 16. Adjusting nuts 20 threadedly engage the shank 18 on either side of the bulb-supporting member 16 and serve for vertical adjustment of the socket 17. The socket 17 carries a lamp 21.

At the opposite end of the base member 10, a downwardly-extending portion 22 has fastened thereto a leaf spring member 23, said member extending over the end of the bulb-supporting member 16 and carrying a thumbscrew 24 passing through an opening therein. The screw 24 has a head 25 engaging the upper surface of the spring 23 and the shank thereof threadedly engages the bulb-supporting member 16. The spring 23 and screw 24, therefore, form a resilient support for the otherwise free end of the bulb-supporting member 16. A second leaf spring 26 is also fastened to the portion 22 of the base member and engages the upper surface of the bulb-supporting member 16, exerting a downward pressure thereon.

The springs 23 and 26 exert opposing forces upon the bulb-supporting member 16, the spring 23 tending to support the said member and the spring 26 urging said member downward. The tension upon these springs, therefore, determines the natural period of vibration of the bulb-supporting member 16.

upon its supports. By changing the adjustment of the thumbscrew 24, this frequency may be varied to bring it out of harmony with the frequency of exterior vibrations. 5 By this means a large amount of extraneous noise in the amplified sound is prevented.

It will be noted that the spring 23 is relatively longer than the spring 26. Because of the length of the spring 23, a relatively large 10 displacement thereof, by operation of the screw 24, will cause only a slight displacement of spring 26. The adjustment of the screw 24, therefore, does not cause a substantial change in the position of the bulb-supporting member 16. The adjustment of the filament position of the bulb 21 is, therefore, not substantially disturbed by the adjustment of the springs 23 and 26.

Various departures may be made in the 20 details of the invention herein illustrated without departing from the broader features thereof as defined by the following claims.

The invention claimed is:

1. A mounting for an exciter bulb including a bulb-supporting member, a flexible support for supporting one end of said bulb-supporting member, a pair of spring members adapted to exert opposing forces upon the opposite end of said bulb-supporting member, 30 and a single adjusting means for simultaneously varying the tension of said springs, said springs being proportioned in size and strength so that movement of said tension-varying means deflects said springs without substantial movement of said bulb-supporting member.

2. A mounting for an exciter bulb including a bulb-supporting member, a hinged support for supporting one end of said bulb-supporting member, a pair of spring members adapted to exert opposing forces upon the opposite end of said bulb-supporting member, and a single adjusting means for simultaneously varying the tension of said springs, 40 said springs being proportioned in size and strength so that movement of said tension-varying means deflects said springs without substantial movement of said bulb-supporting member.

3. A mounting for an exciter bulb including a base member, a bulb-supporting member, a flexible support for supporting one end of said bulb-supporting member upon said base member, a leaf spring fastened to said base member and extending to a point above the opposite end of said bulb-supporting member, a screw passing through an opening in the extending portion of said spring and having its head in contact with the upper surface thereof and its shank threadedly engaging said bulb-supporting member for supporting the same, and a second leaf spring fastened to said base member and having a 50 portion in contact with the upper surface of

said bulb-supporting member for exerting a force thereon.

4. A mounting for an exciter bulb including a base member, a bulb-supporting member, a flexible support for supporting one end of said bulb-supporting member upon said base member, a leaf spring fastened to said base member and extending to a point above the opposite end of said bulb-supporting member, a screw passing through an opening in the 70 extending portion of said spring and having its head in contact with the upper surface thereof and its shank threadedly engaging said bulb-supporting member for supporting the same, and a second leaf spring fastened to said base member and having a portion in contact with the upper surface of said bulb-supporting member for exerting a force thereon, said springs being proportioned in size and strength so that movement of said screw deflects said springs without substantial movement of said bulb-supporting member. 75

In witness whereof, I have hereunto affixed my signature.

WILLIAM H. BAUCH.
